ATTORNEY

UNITED STATES PATENT OFFICE.

JOHN W. SPROWLES, OF FRANKFORD, PENNSYLVANIA.

WOOD-LINED PAPER BOX.

SPECIFICATION forming part of Letters Patent No. 224,052, dated February 3, 1880.

Application filed September 7, 1878.

To all whom it may concern:

Be it known that I, JOHN W. SPROWLES, of Frankford, in the county of Philadelphia and State of Pennsylvania, have invented a new and valuable Improvement in Wood-Lined Boxes; and I do hereby declare that the following is a full, clear, and exact description of the construction and operation of the same, reference being had to the annexed drawings, 10 making a part of this specification, and to the letters and figures of reference marked thereon.

Figure 1 of the drawings is a representation of a perspective view of the bottom part or 15 body of the box; and Fig. 2 is a vertical central section of the same with the lid applied.

This invention has relation to boxes for containing ointments and other oily preparations; and it consists in the construction and novel 20 arrangement of an outer case of paper, an inner lining of wood, and between the two a layer of shellac and glue, as hereinafter fully shown and described.

In the accompanying drawings, the letter *a* 25 designates the main or outer wall of the box, which is made of paper. *b* represents the wood lining; and *c* indicates the shellac and glue layer between the two.

In making this box, a paper box is constructed in the ordinary and well-known manner. The interior of this box is then covered 30 with a layer of shellac, which is allowed to dry. Then upon the shellac glue is applied, and the wooden lining *b* is laid inside around 35 the box upon the glue, which serves to secure this lining in position. The rabbet *e*, or lip extending upward from the edge of the box to engage with the rim of the cover or lid *d*, is formed by the uppermost portion of the wooden 40 lining, which is cut wider than the wall of the box for this purpose. The rim of the lid is not lined with wood, and when it is in position

over the wood extension or lip *e* meets the upper edge of the box-wall in a neat joint. The bottom of the box is lined with wood, 45 shellac and glue being interposed between the lining and the box-bottom, as stated. The top or lid of the box is lined with waxed paper, as indicated at *g*, and a layer of shellac is also applied inside the lid before the waxed 50 paper lining is put on.

The object of this invention is, mainly, to provide a box which will contain ointment without allowing it to exude to the outside, thereby weakening the box, and rendering it 55 liable to break down under slight pressure, as well as making it an unpleasant object to handle. This object is well accomplished in the box which I have described.

Sometimes I may prefer to line the top of 60 the lid also with wood; but as the ointment is not usually so much in contact with this portion of the box the waxed paper will usually be found sufficient.

I am aware that wooden boxes have been 65 covered with paper in order to give them a neat or ornamental appearance, and I do not claim such invention.

What I claim, and desire to secure by Letters Patent, is—

A paper box for ointment or like substances, having a layer of shellac on its interior surface, then a layer of glue on the shellac, and an interior lining of wood secured by the glue and extending above the exterior paper wall 75 to form a lid-bearing, substantially as specified.

In testimony that I claim the above I have hereunto subscribed my name in the presence of two witnesses.

JOHN W. SPROWLES.
